(Cl. D71—1)

To all whom it may concern:

Be it known that we, Herbert L. Bowers and Robert A. Wolf, citizens of the United States, residing at Kenmore, county of Erie, State of New York, have invented a new, original, and ornamental Design for an Airplane, of which the following is a specification, reference being had to the accompanying drawings, forming a part thereof.

Figure I is a top plan view of an airplane showing our new design.

Figure II is a front elevational view;
Figure III is a side elevational view of the design shown in Figure I.

Figure IV is a rear elevational view thereof.

We claim:

The ornamental design for an airplane, as shown.

HERBERT L. BOWERS.
ROBERT A. WOLF.
